UNITED STATES PATENT OFFICE.

TOMOAKI KUWADA, OF AOYAMA, TOKYO, JAPAN.

AUTOMATIC-STOKING SPIRAL BOILER.

1,291,935.

Specification of Letters Patent. Patented Jan. 21, 1919.

Application filed December 4, 1917. Serial No. 205,312.

To all whom it may concern:

Be it known that I, TOMOAKI KUWADA, engineer, subject of the Emperor of Japan, residing at No. 15 Takagi-cho, Aoyama, Tokyo, Japan, have invented new and useful improvements in Automatic-Stoking Spiral Boilers, of which the following is a specification.

This invention relates to an automatic stoking spiral boiler, which may be used as a steam boiler, steam-heater, hot air range, and the like, and which is composed of a centrally located coal-storing cylinder (cylindrical coal bunker), surrounded by a group of spiral water tubes alternately arranged with similarly shaped flues, all so constructed that the burning gases ascending from the furnace below pass through the said flues, transferring their heat to the water in the adjacent water tubes, and finally escaping into a smoke chamber provided on top; the said coal-storing cylinder is provided with a number of spirally cut slots to correspond with and fit to each of the flues, the slots normally facing the walls of the water tubes; the space inside the coal-storing cylinder and the flues being thus partitioned the one from the other by the walls of the flues, but when necessary to clean the flues the latter are brought into free communication with the space inside the coal-storing cylinder by slightly rotating the said cylinder.

The objects of the invention lie in increasing the heat-transferring efficiency of the heating surface by making the flues in spiral fashion, in effecting the cleaning of the flues more easily, and also in attaining automatic stoking action by letting the combustibles supplied to the coal-storing cylinder gradually fall as they burn.

With a view to attain the objects of this invention, types No. 1 and No. 2 have been designed, as illustrated in the appended drawings.

Figures 1 to 6 inclusive are drawings showing type No. 1, while Figs. 7 to 11 inclusive are those showing type No. 2.

Fig. 1 is a vertical section of the boiler.

Fig. 2 is a horizontal cross-section at 2-2 of Fig. 1.

Fig. 3 is a horizontal cross-section of the same at 3-3.

Fig. 4 is a perspective view of the whole.

Fig. 5 shows an elemental segment forming the spiral water tubes.

Fig. 6 is a perspective view of the coal-storing cylinder.

Fig. 7 is a vertical section of the boiler.

Fig. 8 is a front elevation.

Fig. 9 is a horizontal section at 9-9 of Fig. 7.

Fig. 10 is a horizontal section at 10-10 of the same.

Fig. 11 shows a perspective view of the inside of the boiler.

In the above figures the same indices show the same parts.

The structure of this boiler may be divided into three parts, the furnace, the boiler proper, and the smoke chamber.

Type No. 1.—The boiler is constituted by a number of spirally bent elementary segments *a* of the same shape, which are grouped together to form a cylindrical boiler. Each segment *a* has a water channel *h* of T-shaped cross-section, and ports *b* are provided at both the upper and lower ends and on both faces of the segment, so that when all the segments are grouped together all the parts will fit each other, making water-tight joints, the outer faces of the segments also making a continuous periphery and forming a cylindrical space at the center, when the whole constitutes a set of spiral flues *i* formed by any two adjacent segments. The heating surface thus formed by the walls of the spiral flues *i* is impinged upon by the gases of combustion ascending from below. Therefore, when compared with a simple vertically arranged heating surface, the effectiveness of the heat transfer of the heating surface is considerably increased. In other words, by this method of construction a greatly increased heating surface can be obtained from a boiler of given volumetric dimensions.

Tightening bands *g* are employed at the upper and lower parts of the boiler in a suitable manner, to tighten and retain the group of the segments *a* in their proper position. The coal-storing cylinder (cylindrical coal bunker) *c* is provided with a number of spirally cut slots *j* which are of the same shape as the spiral flues *i*. When the cylinder is inserted into the central space formed by the group of segments, its spiral slots *j* exactly fit and face the walls forming the water tubes *h* and the flues *i* are shut off from the central space by the peripheral wall of the coal-storing cylinder *c*.

When the coal-storing cylinder *c* is

slightly rotated, each of the spiral slots *j* coincides with each of the flues *i*, and the flues *i* are brought into free communication with the inside of the coal storing cylinder *c*. Thus the communication between the flues *i* and the coal-storing cylinder *c* is obstructed, when fuel is being fed into the cylinder *c*, and again that communication can be obtained by rotating the cylinder *c* a little, when it is desired to clean the inside of the flues *i*. The coal-storing cylinder *c* is supported at the top of the smoke chamber by means of a ring-shaped rim *k*, and a cover *l* is provided on top of the cylinder, whereby the coal cylinder *c* can be easily rotated from outside, facilitating the feeding of fuel as well as cleaning the flues *i*. The furnace is composed of two parts, an outer and an inner casing. The inner casing is supported on top and inside of the outer casing in a suitable manner, and in turn supports the grate *f*. Around the outer casing and near the upper edge thereof are provided numerous ventilation holes *e*, through which air is admitted around the heated portion surrounding the inner casing into the furnace from below the grate *f*. The furnace may be constructed in the ordinary fashion without any inner casing, as shown by the illustration of type No. 2 boiler. The provision of a fire-door *m* and ash-door *n* is not different from common furnaces.

The smoke chamber *d* is located on top of the boiler and embraces the upper opening of all the flues *i*. At the center is a circular hole to receive the coal-storing cylinder *c*, and toward one side an exhaust port *o*, leading to the chimney.

Type No. 2 differs from type No. 1 in that the boiler proper of the latter is composed of a group of elementary segments *a*, each of which constitutes the water tubes *h*, whereas in the former the water tubes *h* and flues *i* are constructed in a single solid

body, forming an inside structure *q*, although of the same spiral shape; and this is inclosed by a boiler-drum *p*, the water being admitted into the space between this boiler-drum *p* and the inside structure *q*. The aforementioned inclosing drum *p* may be dispensed with, and the spiral inside structure *q* alone may be immersed in water, thereby accomplishing the function of boiling the water. 50

Claims:

1. A boiler comprising a plurality of water tubes of spiral formation secured together in boiler formation to provide spiral flues and a central fuel receiving chamber, and a fuel storing member removably mounted in said chamber and formed with slots of spiral formation which coincide with said flues. 60

2. A boiler comprising a plurality of water tubes of spiral formation secured together in boiler formation to provide spiral flues and a central fuel receiving chamber, and a fuel storing member removably mounted in said chamber and formed with slots of spiral formation which correspond with said flues, said member being rotatably mounted in said chamber and capable of occupying one position wherein said slots coincide with said flues and another position 75 wherein said slots do not coincide with said flues. 70

3. A boiler comprising a plurality of water tubes arranged to form a central fuel receiving chamber, a plurality of spiral flues, and a fuel storing member rotatably mounted in said chamber and capable of occupying two positions, said member being formed with slots corresponding to said tubes whereby said member covers or uncovers said flues according as it occupies one position or the other. 80 85

In testimony whereof I have signed my name to this specification.

TOMOAKI KUWADA.
